(57) **CLAIM**

The ornamental design for a clamp, as shown and described.

DESCRIPTION

FIG. 1 shows a perspective view of my design for a clamp; FIG. 2 is a front end view thereof; FIG. 3 is a rear end view thereof; FIG. 4 is a side view thereof; FIG. 5 is an opposite side view thereof; FIG. 6 is a bottom view thereof; and, FIG. 7 is a top view thereof.

The broken line showing of a turn screw in FIG. 3 is for illustrative purposes only and forms no part of the claimed design.
